APPARATUS FOR CLEANING FIBROUS MATERIAL

Alv Westelius Bernhart, New Orleans, La., assignor to Mainmast Securities, Limited, Toronto, Ontario, Canada, a company of Ontario

Application June 12, 1950, Serial No. 167,670

5 Claims. (Cl. 19-7)

1

The invention relates to improvements in apparatus for cleaning fibrous material, as described in the present specification and shown in the accompanying drawings that form a part of the same.

Heretofore in the treatment of fibre bearing plants for the purpose of liberating the useful fibres, which in some plants form the outer covering for the woody and gummy material requiring to be removed and which in some plants lie between a tough outer bark and a woody and gummy interior, the cleaning process has consisted principally in subjecting the stalks to crushing, bending, breaking, combing and other harsh treatments, either dry or in the presence of liquid, and in the succession and manner provided for in the particular type of apparatus made available for the purpose, so as to reduce the fibres to ribbon form.

While the above-suggested steps in the treatment of the stalks are useful and in fact seem necessary in the dislodgement of the bulk of the woody and gummy particles from the stalks and to reduce the fibres to a ribbon, or sliver, state, such treatment if continued thereafter would not only fail to result in the further necessary material refinement of the fibres but would result in damage to the fibres as well as tending to separate the endwise aligned fibres and thus break the continuity of the ribbon.

I have found that once the fibres have been reduced to ribbon form any unwanted substance still adhering thereto can be most readily removed by subjecting the ribbon to gentle scraping treatment on both surfaces without occasioning any appreciable longitudinal pull such as would separate the overlapping ends of the by now lengthwise aligned fibres, so that in effect long ribbons of cleaned fibres are finally obtained. In so far as I am aware no satisfactory apparatus for treating the ribboned fibres has yet been proposed or made available.

It is accordingly the main object of my invention to provide simple and practical means for cleaning the fibres after they have been reduced to ribbon, or sliver, form, such means being adapted for operating on the fibres either in a dry condition, or in solution, and being equally effective during the bleaching and rinsing processes.

Broadly, in method, the present invention consists in passing a ribbon of fibre one or more turns around a driven hollow drum or like device, lengthwise of a circumferentially extending opening, or a series of circumferentially spaced

2

openings, in said drum whereby that portion of the ribbon across said opening will lie within the plane of the interior face of the drum and will upon the rotation of said drum be drawn across and scraped by a stationary scraper blade, or blades, located within the drum.

With the above and other objects in view the invention consists in the novel features of construction, arrangements and combinations of parts set out in the present specification and particularly pointed out in the claims for novelty which follow.

In describing the invention reference will be had to the accompanying drawings, in which:

15 Figure 1 is an elevational view of one side of my apparatus, with the near side wall removed and the whole being shown diagrammatically.

Figure 2 is a plan view of the lowermost of the tanks shown in Figure 1.

20 Figure 3 is an enlarged side elevation, partly in longitudinal section, of one of the rotatable ribbon advancing drums and its interiorly mounted stationary scraper.

Figure 4 is an enlarged longitudinal sectional view through three associated scraper units, taken substantially on the line 4-4 of Figure 2.

Figure 5 is a broken perspective view of one of the revolving ribbon carrying drums.

Figure 6 is a broken perspective view of a modified form of drum.

Like numerals of reference indicate corresponding parts in the various figures.

Referring to the drawings, in which a complete embodiment of the invention is shown, 1 indicates a driven combing element such as is commonly used in decorticating mechanism of known type to reduce fibrous stalks to sliver, or ribbon, form and which may well serve in combination with a pair of rollers 2 as the means to 35 deliver a sliver to the novel combined advancing and scraper element A, which latter in cooperation with other such elements will serve to move the sliver, or a number of such slivers forwardly through a tank, or a series of tanks, and during 40 such movement will cause the sliver, or slivers, to be scraped along opposite surfaces.

Each of the elements A, of which there may be any desired number arranged in parallel relation to one another transversely within the 45 tank B, or within a series of tanks, as will be described in greater detail hereinafter, consists of a fixed shaft 4 mounted at its ends against rotation in the opposite sides of the tank, a plurality of radial scraper arms 5 of equal length fixed 50 to said shaft and each carrying on their respec-

tive ends one or more scrapers 6 extending parallel to the axis of said shaft, and a hollow drum 7 mounted for rotation around the said shaft. The inside diameter of the drum is such that on the rotation of the drum its inner periphery will pass the blades 6 but with no appreciable distance therebetween so that in effect the blades will be swept by the drum as the latter is rotated.

In order that the drum may function to advance the sliver and, further, that the scraping operations may be accomplished during such advance the sliver is given at least one turn around the drum and at (preferably four) points traversed by the sliver circumferentially of the drum the wall of the latter is cut away, to provide openings 8 which will break the circular continuity of the outer periphery of the drum and thus cause the tightly drawn sliver to assume, while passing over each such opening, a straightened path which will lie within the plane of the inner periphery of the drum and within reach of the scraper blades 6, so that as the drum is rotated the portions of the sliver which are currently across the openings as the latter come into alignment with the blades will be thoroughly scraped.

In order that the greatest scraping effect may be obtained within a given length of tank it is preferable that the sliver be traversed back and forth within the tank a number of times and this is accomplished by the provision of as many of the elements A as is practical, mounted transversely of the tank and by reeving the sliver around the drums of the said elements successively from end to end of the tank and back and forth as many times as the width of the tank will permit. Such an arrangement is clearly shown in Figure 2.

It is of course obvious that each successive passage of the sliver lengthwise of the tank will make necessary the provision of a new series of circumferentially disposed cutouts 8 in each drum, each further along the length of the drum from the point of entry of the sliver into the tank.

If desirable, either for the purpose of guiding the sliver around the drum, or for the purpose of reducing the thickness of the wall of the drum to insure the sliver lying within the plane of the inner periphery of the drum when across an opening 8, the outer surface of the drum may be provided with a groove 9, or grooves, and such groove, or grooves, may extend in spiral form completely around the drum to include the respective openings of a series. It is desirable in all cases that the bottom of a groove be flat in order that the sliver may assume a strap-like form and thus present a flat surface to the scraper blades.

It is of course apparent that the scraper blades may be of uninterrupted length to take in all of the openings 8 lengthwise of the drum, or they may be in short lengths to lie beneath the openings they serve only. As it is a mere mechanical expedient to effect this difference it has not been thought necessary to make a separate showing in the drawings to illustrate the two forms.

As the process carried out in a tank is to a specific purpose and usually in the presence of a liquid, such as boiling water, and as when more than one tank is employed and each using a different liquid, or similar liquids at different temperatures, it is very desirable that in each the scraping process be extended to both surfaces of the sliver and this is accomplished by reversing the direction of the turn, or turns, of the sliver

5 around successive drums and by directing the rotation of the drums accordingly. This is shown with clarity in Figure 4 in which the sliver being moved from left to right is reeved over the top of the drum at the left and after making one full turn around the drum is reeved around the under side of the next succeeding drum and after making a complete turn of this drum passes upwardly and is reeved around the top of the next drum and after one complete turn around this last drum passes in a downward direction for contact with the under side of the next drum (the latter not shown). All of the drums receiving the sliver at their top sides are rotated in one direction while all of the drums receiving the sliver at their under sides are rotated in the opposite direction. In this manner the surfaces of the sliver are alternately scraped.

20 The particular means for causing the rotation of the various drums is not a feature of the present invention and as the operation can be successfully carried out in many well-known ways it is not thought necessary to show any specific means in the drawings for so doing, other than to show that each drum may be provided with a fixed gear or wheel 10 for contact with a driving medium.

25 In Figure 5 the drum is shown as having a spiral groove 11 therein with the bottom thereof broken at intervals, as at 12, to permit of the sliver passing inwardly into contact with the scraper blades.

30 In Figure 6 the drum is shown as having circumferentially spaced openings 13 across which the sliver is adapted to straighten out for contact with the scraper blades, and the drum is not grooved between said openings.

35 In Figure 6 but one scraper arm is shown but it must be understood that more may be employed, as shown for instance in Figure 4.

40 In the use of this invention the respective tanks B, C and D in which the members A are mounted are first supplied with the appropriate liquids in accordance with the requirements of the steps of the process to be carried out therein; for example, the tank B is primarily a scraper tank and is partially filled with boiling water; the tank C may be used for bleaching purposes and is therefore provided with a bleaching agent, while the uppermost tank D may be used as a rinsing tank with water again used as a rinsing medium.

45 After the drums 7 have been set in motion with alternate drums operating in the opposite direction to that taken by the remaining ones the sliver is reeved around the drums successively in alternating forward and rearward directions back and forth throughout the length of each tank and between a pair of guide rollers 14 and over a guide roller 14a positioned between the tanks B and C at the delivery end of the tank B and between the pair of guide rollers 15 and over the guide roller 15a positioned between the delivery end of the tank C and the receiving end of the tank D.

50 As the rotation of the various drums proceeds the sliver is advanced by each drum and in the advance the pull on the sliver causes those portions thereof which extend over the openings in the drums to extend straight across the said openings and thus lie within the planes of the inner peripheries of the drums so that the sliver will be drawn across the scraper blades of the respective drums and thoroughly scraped again and again throughout the passage of the sliver through the various tanks. As each successive drum is rotated in a direction opposite to that

of the next preceding drum the sliver will be scraped on opposite sides alternately.

When the sliver has passed from the delivery end (D) it is picked up between sets of rollers, indicated generally at 16, by means of which it is pressed to squeeze excess liquid therefrom before it is passed to the drying room, or to any appropriate device for further treatment.

While I have shown and described my invention as embodied in the forms which I at present consider best adapted to carry out its purposes, it will be understood that it is capable of modifications, and that I do not desire to be limited in the interpretation of the following claims except as may be necessitated by the state of the prior art.

What I claim is:

1. In apparatus for cleaning fibrous material, a rotatable frame for advancing a sliver of material reeved therearound, said frame having a circumferential groove for the reception of said sliver, said frame having an opening therein across which said sliver is adapted to pass within the plane of the inner face of said frame, and stationary scraper means within said frame adapted to scrape the face of the portion of the sliver lying in said opening each time the said opening is brought into register with said scraper means in the rotation of said frame.

2. Apparatus for cleaning fibrous material, as set out in claim 1, in which the bed of said grooves is flat whereby the material passing thereover will be held to ribbon-like form.

3. In apparatus for cleaning fibrous material, a driven drum adapted to receive a turn of fibrous material in sliver form, said drum having a plurality of elongated openings arranged circumferentially thereof across which said sliver is adapted to lie within the plane of the inner face of said drum, a fixed shaft constituting the support for said drum and around which said drum is adapted to be driven, a plurality of arms radiating from said shaft, and scraper blades carried at the outer ends of said arms and extending parallel with said shaft, said blades being adapted to lie in the paths of those portions of the sliver exposed in said openings for scraping the sliver on the rotation of said drum.

4. Apparatus for cleaning fibrous material, com-

prising a tank, a plurality of alternate clockwise and anti-clockwise-driven drums arranged in parallel within said tank, each said drums receiving a complete turn of said sliver therearound, the reeving approach of said sliver to successive drums being alternately over and under said drums whereby the opposite faces alternately of said sliver will lie innermost against said drums in succession, the said drums having spaced circumferentially arranged openings therein across which the sliver is adapted to lie within the plane of the inner faces of the drums, and stationary scraper means positioned within the respective drums for scraping contact with the portions of the sliver exposed in said openings during passage past said scrapers.

5. Apparatus for cleaning fibrous material, comprising a tank adapted to contain a cleaning fluid, a plurality of fixed shafts arranged in parallel transversely of said tank, drums mounted on said shafts respectively and rotatable therearound in successively opposed directions, said drums having a number of spiral grooves in the outer faces thereof spaced lengthwise of said drums and each said groove being adapted to receive a turn of said sliver whereby said sliver may be advanced backwardly and forwardly from end to end of said tank, said drums being provided with circumferentially spaced elongated openings whereby the portions of said sliver lying across said openings in the rotation of said drums will extend in straight lines between the ends of the respective openings and thereby lie within the planes of the respective inner faces of the drums, and fixed scraper means within the respective drums for scraping contact with the inner faces of the portions of said sliver exposed in said openings.
